UNITED STATES PATENT OFFICE.

ARTHUR EDWARD BARTON SMITH, OF HANDSWORTH, BIRMINGHAM, ENGLAND.

FRAMING OR MOUNTING OF PHOTOGRAPHS, PICTORIAL CARDS, AND THE LIKE.

1,210,226.

Specification of Letters Patent. Patented Dec. 26, 1916.

Application filed September 7, 1915. Serial No. 49,276.

To all whom it may concern:

Be it known that I, ARTHUR EDWARD BARTON SMITH, a subject of the Kingdom of Great Britain, residing at 140 Finch road, 5 Handsworth, Birmingham, in the county of Stafford, England, have invented certain new and useful Improvements in and Relating to the Framing or Mounting of Photographs, Pictorial Cards, and the like, of 10 which the following is a specification.

This invention relates to the frames or mounts of photographs, pictorial cards, and the like, and is an improvement on that type of frame or mount which is effected by 15 rounding the picture front glass and back or the picture itself with flexible material, such as paper or the like, which is folded over and adhesively secured on the backing.

By the present invention a frame of metal, 20 wood, celluloid, or similar material can be readily formed around the picture, and is easily secured in position by means of flexible adhesive attachments, thereby forming a cheap and easy means of framing which can 25 be readily effected by an amateur without the necessity of exercising any skill.

In order that this invention may be clearly understood and readily carried into practice, reference may be had to the appended explanatory sheet of drawings, upon which:—

Figure 1 is a rear elevation of a frame according to the present invention assembled in position around a picture. Fig. 2 is a vertical section on line 1—2 of Fig. 1. Fig. 35 3 is a front view of one frame length partly broken away.

In an embodiment of this invention the two sides, top and bottom of the frame α are formed of channel section in separate 40 lengths, the ends α^1 being mitered to form a butt joint at the corners. The width of the recess in the channel α is equal to the average combined thickness of the glass b , picture c and backing d .

45 For the purpose of preventing the dis-

placement of the top, bottom and sides, the rear flange of each length of channel α is provided with one or more slots α^2 at any desired position, and through each of these slots α^2 a length or portion of paper, linen 50 or other flexible material e is threaded, after which the ends of the flexible material are adhesively connected together, thus forming flexible projecting tabs e , which after the top, bottom and sides α are placed in position are securely fastened to the outer face 55 of the backing d or in the case of the backing being dispensed with, to the outer face of the back of the picture by means of any suitable adhesive substance such as gum, 60 glue or the like.

Advantageously the tabs e are provided with extensions or reduced tongue portions e^1 which are threaded through slots α^2 in the frame portions α and folded back on to the 65 main or wider portions of said tabs to which they are securely fastened advantageously by adhesive. By these means the top, bottom and sides are retained in their position, and are prevented from working free of the 70 rigid embrace of the glass, picture and backing.

What I claim as my invention and desire to secure by Letters Patent is:—

In a picture frame of the character described, in combination, a frame of channeled sections adapted to receive the glass, picture and backing, and provided with slots, strips passed through said slots and tabs to which the ends of said strips are secured 75 80 adapted to be secured to the backing of the picture, substantially as described and for the purpose set forth.

In witness whereof I have hereunto set my hand in the presence of two witnesses.

ARTHUR EDWARD BARTON SMITH.

Witnesses:

ARTHUR HENRY BROWN,
HOLLIS BROWN.
